UNITED STATES PATENT OFFICE.

JULIUS BEHR, OF FEUERBACH-STUTTGART, GERMANY.

RADIATOR.

1,351,462.

Specification of Letters Patent. Patented Aug. 31, 1920.

Application filed April 24, 1915, Serial No. 23,733. Renewed February 17, 1920. Serial No. 359,231.

To all whom it may concern:

Be it known that I, JULIUS BEHR, a subject of the German Emperor, and resident of Feuerbach-Stuttgart, Germany, have invented certain new and useful Improvements in Radiators, of which the following is a specification.

My invention relates to radiators comprising interchangeable cooling elements, and a primary object is to provide an improved readily detachable hollow coupling for connecting the ends or terminals of the cooling elements with the headers of the radiator such that one-sided tension is prevented from being set up in the thin walls of the elements and a firm connection is insured without the walls being torn apart. To this end I provide that a pipe fixed on a header or on a terminal is surrounded by a ring carried by the other of these two members, and a chamber which is in open communication with both the header and the terminal is formed in the ring by means of packing locked in position by one single screw or by means of the screw itself.

To this and other ends, the invention consists in the construction, arrangement and combination of parts described hereinafter and pointed out in the claims.

One form of my invention and modifications thereof are represented by way of example in the accompanying drawing, wherein:

Figure 1 is a front elevation of one form of my improved radiator, some of the cooling elements having been removed and lateral members being shown in section.

Fig. 2 is a vertical cross-section taken on the line 2—2 in Fig. 1, and

Fig. 3 is a vertical cross-section, enlarged, showing the improved connection of a cooling-element terminal with the header;

Figs. 4 and 5 are like sectional views, enlarged, showing modifications of the connection shown in Fig. 3.

Referring to the drawing, *a* designates the headers of the radiator and *b* recesses which are provided therein. Instead of individual recesses *b* one continuous recess running from end to end of the header may be employed if desired. The headers or terminals *c* of the interchangeable tubes *d* having very thin walls, are fitted into said recesses *b*. The depth of the tubes *d* is preferably the same as that of the upper and lower headers *a*, so that the front and rear faces of the

tubes are flush with those of the headers, as shown in Fig. 2. The headers *a* are provided with lugs *e* which may be carried by bars *f* of U-section. These bars are mounted on the frame of the car and thus serve to connect the upper and lower headers *a* and to support the radiator as a whole on the frame of the car. Consequently, it is possible to take the entire radiator readily apart, so that interchangeable members may be assembled, without employing any solder, merely by the use of screws.

In the construction represented in Fig. 3 a pipe *g* is screwed into the wall of the header *a* in one of the recesses *b*, said pipe being provided with a number of openings *h* in its circumference for the passage of the cooling medium. A rubber ring *i* is first placed around the pipe *g*, and then the terminal *c* of the interchangeable cooling element is fitted upon said pipe by means of its annular member *k* surrounding the pipe at the openings *h* and abutting against the rubber ring *i*. The packing ring *i'* is thereupon placed on the pipe *g* and, finally, the outer end of the latter is closed by means of a threaded plug *l*, which simultaneously compresses the packing rings *i* and *i'* and firmly connects the cooling element with the header.

In the modification shown in Fig. 4 the header *a* is also recessed at *b*, and in addition has an annular member *m* projecting from it. The interchangeable cooling element *c* terminates in the tubular member *n* having openings *o* for the passage of the cooling medium. The tube *n* communicates with the interior of the cooling element, it being mounted within the annular member *m* and held in position by means of rubber packing rings *i* and *i'*. In this manner the tube *n* and with it the cooling element is yieldingly connected with the header *a*. At the same time electrical insulation is provided between the cooling element and the header *a*. A plug *l* is employed similarly as in Fig. 3 for locking the rings *i* and *i'* in position.

In the modification shown in Fig. 5, the same reference characters are employed as in Fig. 3 and 4 for similar parts. A flanged tubular member *q* is screwed in a recess *b* into the wall of the upper header *a*, its flanged end being located in the annular member *k* provided on the end of the interchangeable cooling element *c*. A rubber

packing ring *i* is interposed at one side of the ring *k* to form a yielding connection between the members *k* and *q*.

The other side of the ring *k* is closed by the plug *l* screwed not into the tubular member as shown in Fig. 3, but directly into the ring surrounding the same. For the purpose of electrically insulating the ring *k* from the flange of the member *q* an additional rubber ring *z* is preferably inserted. This ring *z* may, however, be omitted if no electrical corrosion is to be feared, as is the case if the same metal is used for the several parts.

15 I claim:—

1. In a radiator, the combination with a cooling element comprising an upper header, a lower header and a plurality of tubes having very thin walls opening into the same, of an upper and a lower header, an upper tubular member securely carried by and opening into one of the upper headers, the other of the upper headers having an annular member surrounding said tubular member, a lower tubular member securely carried by and opening into one of the lower headers, the other of the lower headers having an annular member surrounding the lower said tubular member, and elastic packing rings locked between each tubular member and the adjacent annular member for forming chambers in the annular members, each chamber being in open communication with the adjacent tubular member and with the header carrying the respective annular member containing the chamber, said upper

and said lower tubular member each constituting a tightening or bolting and a supporting member.

2. In a radiator, the combination with a cooling element comprising an upper header, a lower header and a plurality of tubes having very thin walls opening into the same, of an upper and a lower header, an upper tubular member securely carried by and opening into one of the upper headers, the other of the upper headers having an annular member surrounding said tubular member, a lower tubular member securely carried by and opening into one of the lower headers, the other of the lower headers having an annular member surrounding the lower tubular member, elastic packing rings locked between each tubular member and the adjacent annular member at one side of the latter for forming chambers in the annular members, and removable closure means at the other side of the annular members, each chamber being in open communication with the adjacent tubular member and with the header carrying the respective annular member containing the chamber, said upper and said lower tubular member each constituting a tightening or bolting and a supporting member.

In testimony whereof I have hereunto set my signature in the presence of two subscribing witnesses.

JULIUS BEHR.
